WRAPPING MACHINE

John Van Buren, Brooklyn, N. Y.

Application September 8, 1934, Serial No. 743,199

10 Claims. (Cl. 93—2)

This invention relates to wrapping machines and particularly to machines for wrapping boxes.

The invention has for its salient object to provide a machine of the character described so constructed and arranged that the wrapper will be tightly folded and secured around the box or container.

Another object of the invention is to provide folding and securing means in a machine of the character specified, so constructed and arranged that the folds will be securely held during the wrapping operation and the first folds made will not unfold or become loosened during the forming of the subsequent folds and the securing of the folds around the box.

Further objects of the invention will appear from the following specification taken in connection with the drawings which form a part of this application, and in which

Fig. 1 is an end elevation of the machine constructed in accordance with the invention;

Fig. 2 is a side elevation of the machine shown in Fig. 1;

Fig. 3 is a top plan view of the machine;

Fig. 4 is a plan view of the machine taken substantially on line 4—4 of Fig. 1;

Fig. 5 is a sectional elevation of the folding mechanism;

Fig. 6 is an elevational view taken at right angles to Fig. 5;

Fig. 7 is a view similar to Fig. 5 but showing the end folders in operative position after the upper and lower end tucks have been formed;

Fig. 8 is an elevational view taken at right angles to Fig. 7;

Fig. 9 is a sectional elevation showing a box and wrapper being fed upwardly to the folding mechanism;

Fig. 10 is a view similar to Fig. 9 but showing the box and wrapper in elevated position and about to be fed to the end tucking and folding means; and

Fig. 11 is a view similar to Figs. 9 and 10 but showing the box and wrapper fed upwardly to the folding mechanism and the plunger, which has fed the box and wrapper upwardly, on its downward stroke.

The invention briefly described consists of a machine for folding wrappers around boxes comprising means for feeding the boxes and wrappers, means for successively feeding each box and wrapper upwardly to folding mechanism, successively acting means for placing the upper and lower end tucks in the wrapper and for folding the ends of the wrapper across the tucks and ends

of the box, means for securing the wrapper in folded position and means for discharging the wrapped boxes or articles from the machine.

The lower end tucks are placed in the wrapper by positively actuated but resiliently pressed tucking members and the upper tucks are placed in the wrapper by downwardly movable tucking members which are arranged to move downwardly after forming the upper tucks to a position over the lower tucks, whereupon folding means are brought into action to fold the end folds at one side of the article over the tucks formed therein. These folding means are carried by the same member which carries the means for forming the upper tucks and the latter means are moved out of operating position as the folding means come into operation.

Further details of the invention will appear from the following description.

In the embodiment of the invention illustrated in the drawings, the boxes or containers are fed to the machine by an endless conveyor 20 by which they are deposited successively on a shelf or table 21. This construction is particularly illustrated in Figs. 2, 5 and 6. The table 21 has an opening 22 in the bottom thereof, and is shorter in length than the length of the boxes B.

An end wall 23 is located at the advance end of the table or shelf 21 and forms a stop for positioning the boxes as they are fed upwardly by the conveyor 20.

A plunger 25 is mounted for vertical reciprocation through the opening 22 and is constructed and arranged to periodically feed the forward box upwardly through an opening 26 in a table or support 27 which is disposed above the path of movement of the boxes from the conveyor 20.

The plunger 25 has a head 28 at the upper end thereof and has secured thereto a plate 29 which forms a stop for the next succeeding box when the forward box is being fed upwardly by the plunger.

When the forward box is fed upwardly in the manner just described a wrapper has been deposited on the table 27 by a feeding mechanism and is disposed in the path of upward movement of the box. This feeding mechanism will be hereinafter described.

The plunger 25 is actuated in the following manner: The main drive shaft of the machine is shown in Figs. 2 and 4 at 30. This shaft is operatively connected by gears 31 and 32 to a shaft 33 which is connected by a sprocket 34, chain 35 and sprocket 36 to drive a shaft 37. A disk 38 is fixed to the shaft 37 and carries a pin 39 which is disposed in a slot 40 of an arm 41 mounted on

a fixed pivot 42. As the disk and pin are rotated the arm 41 will be oscillated upwardly and downwardly about its pivot 42. A link 43 is pivoted at 44 to the end of the arm 41 and is pivoted 5 at 45 to the lower end of the plunger 25. Thus, as the link is oscillated the plunger will be reciprocated periodically and will feed successive boxes and wrappers upwardly to the folding mechanism hereinafter described.

10 The feeding and cutting mechanism for the wrapper strip may be constructed in any desired manner, but is illustrated in Figs. 1 and 3 as comprising two sets of feed rolls A and C. The feed rolls A comprise a pair of rolls 50 and 51, the roll 50 having a cutting blade 52 mounted thereon, as shown in Fig. 3. The rolls 50 and 51 are geared together and the roll 51 is driven by a gear connection 53, 54 from a spindle or shaft 55. The shaft 55 is connected by a sprocket 56, chain 57 and sprocket 58 to a shaft 59 which in turn is driven by a bevel gear connection 60, 61 from the shaft 33.

15 The feed rolls C which receive the severed strip are rotated at a slightly faster rate of speed than the feed rolls A and comprise a pair of rolls 62, 63 which are geared together in the usual manner. The roll 63 is mounted on a shaft 64 which is driven by a sprocket 65, chain 66 and sprocket 67 from a shaft 68. The shaft 68 is driven from the shaft 59 by a spur gear connection comprising a pair of gears 69 and 70.

20 By the driving connections above described the paper is fed from the strip or supply roll by the feed rolls A and is severed thereby and is thereafter fed by the feed rolls C to the supporting table 27. Guides 71 and 72 are provided for the sides of the strip and an end stop 73 limits the movement of the strip on the table 27.

25 The forward box when fed upwardly by the plunger 25 carries with it the wrapper which is folded during this feeding movement across the front, back and top of the box in the manner shown in Fig. 6. The two ends of the wrapper extend downwardly below the lower edge of the 30 box.

35 During this upward feeding movement one side of the wrapper is pressed against the back of the box by a presser member 75 which is mounted on a pivot 76 and is resiliently actuated to 40 press the wrapper against the box. The other side of the wrapper is held against the front of the box by a guide plate 77.

45 After the box and wrapper have been fed upwardly to the position shown in Fig. 6, the depending end 80 of the wrapper W is folded across the bottom of the box by means of a plate 81 carried by a slide 82 which is mounted on a pair of rods 83 and 84 slidably mounted in bearings 85. The slide is reciprocated by a link 86 which is 50 connected at its rear end, as shown at 87, to an arm 88 mounted on a fixed pivot 89. This arm has a pin or roller 90 mounted thereon intermediate the ends thereof and disposed in a cam groove 91 formed in a cam mounted on a shaft 55 92. The shaft 92 is driven by a bevel gear connection 93, 94 from a shaft 95. The latter shaft is connected by bevel gears 96 and 97 to a shaft 98 which in turn is connected by bevel gears 99 and 100 to the shaft 37.

60 70 The folding plate 81 will thus be reciprocated periodically to fold the downwardly extending end 80 of the wrapper W across the bottom of the box.

75 After the end W has been folded in the manner above described the box and wrapper will be fed

from the position shown at X in Fig. 6 to the position shown at Y. This feeding operation is performed by a pusher plate 105 which is carried by slide rods 106 and 107 slidably mounted in suitable bearings 108. The pusher plate is actuated 5 by a link 109 which is pivoted at 110 to an arm or lever 111 mounted on a fixed pivot 112 and having mounted thereon intermediate its ends a pin or roller 113. The roller 113 engages a cam 114 and as the cam rotates the arm 111 will be 10 oscillated to cause the pusher plate 105 to feed the box and wrapper from the position shown at X to the position shown at Y in Fig. 6. During this feeding movement the depending end 80A of the wrapper is folded across the folded end 80 by 15 the edge 115 of a hot plate or support 116 which is disposed in alignment with a supporting table 117. The wrapper W used in the particular embodiment of the invention illustrated is waxed and the folded ends of the wrapper will be 20 around the box by the heat of the hot plate 116.

25 After the box and wrapper have reached the position Y shown in Fig. 6 the upper and lower ends of the wrapper are tucked against the ends of the box and the projecting ends of the wrapper are thereafter folded across the tucked ends and across the ends of the box. This is accomplished in the following manner:

30 The lower ends of the wrapper are tucked upwardly against the ends of the box by tuckers 121 which are mounted on pivots 122 carried by arms 123 which in turn are mounted on shafts 125 and 126. The tuckers 121 are resiliently actuated by springs 127 and are provided with depending 35 portions 128 which by engagement with the arms 123 limit the movement of the tuckers by the springs 127.

35 The shafts 125 and 126 are periodically oscillated in the following manner: This construction is particularly illustrated in Figs. 5 and 6 where- 40 in it will be seen that the shafts 125 and 126 are connected by bevel gears 129, 130 and 131, 132 to a shaft 133. The shaft 133 has mounted on one end thereof a crank arm 134 which is connected to a pitman 135. The pitman 135 has its other end bifurcated, as shown at 136, the bifurcated end of the pitman extending on opposite sides of the shaft 33. A roller 137 is carried by the pitman 135 and is disposed in and driven by a cam 138 mounted on the shaft 33. 50 As the pitman is actuated by the cam the tuckers 121 will be moved upwardly from the position shown in Fig. 7 to the position shown in Fig. 5 and will tuck the lower ends of the wrapper upwardly against the lower portions of the ends 55 of the boxes.

55 After the lower tucks have been formed in the manner just described the upper tucks will be formed by tucker blades 140 and 141. These blades are carried by sleeves 142 and 143 which 60 are slidably mounted on vertically disposed square shafts 144 and 145 which are supported in a frame 146 and in brackets 147 and 148 depending from the frame.

65 The tucker blades are vertically reciprocated by arms 150 and 151 which are mounted on a spindle 152. The arms 150 and 151 are connected by a cross rod 153 to which is pivoted a pitman 154 which is bifurcated at its lower end and straddles the shaft 33 and is provided with a 70 roller 155 disposed in a cam 156 mounted on the shaft 33. As the cam rotates the pitman will be vertically reciprocated and will oscillate the arms 150 and 151 about the pivot shaft or spindle 152. The arms 150 and 151 are pivoted at their ends to 75.

yokes or collars 157 which encircle and are disposed in grooves in the sleeves 142 and 143. The uppermost position of the tucker blades 140 and 141 is shown in Fig. 6 in dotted lines and after 5 the box and wrapper have been fed to the position Y the blades are moved downwardly from the dotted line position to the position shown at Y in Fig. 10. In this position it will be noted that the blades 140 and 141 have formed the upper 10 tucks in the wrapper and have moved downwardly to the position overlapping the lower tucks.

After the upper and lower tucks have been formed the end folds along the rear edges of the box are folded across the ends of the box in the 15 following manner: The sleeves 142 and 143 in addition to carrying the tucker blades 140 and 141 also carry folding members or spindles 160 and 161. The spindles 160 and 161 are mounted on the ends of arms 162 pivoted at 163 on lugs 20 164 formed on the sleeves 142 and 143. The arms 162 are extended beyond the pivots 163 in the form of extensions or arms 165 which are resiliently actuated by springs 166. The springs press the spindles toward the ends of the box but 25 this movement is limited by fixed guide strips 167.

The spindles 160 and 161 are moved toward and away from operative position by the rotation of the shafts 144 and 145. These shafts are connected by bevel gears 170 and 171 to a shaft 172. 30 The shaft 172 is periodically oscillated by an arm 173 which is connected to a pitman 174 having thereon a roller 175 actuated by a cam 176 mounted on the shaft 92. The various operative parts of the machine including the cams are so timed 35 that after the upper and lower end tucks are placed in the wrapper and the tucking blades 140 and 141 have been moved downwardly to their lowermost positions, the shafts 144 and 145 will be rotated or oscillated by the driving connections just described to move the spindles 160 and 161 across the ends of the box and wrapper, thus 40 folding the wrapper across the ends of the box. When this has been accomplished the article or box and wrapper are fed forwardly by the actuation 45 of the pusher plate 165 and the remaining end folds will be formed by the engagement of the projecting ends of the wrapper with hot plates 180 which are disposed at the side edges of the path of movement of the wrapped article. As 50 the projecting folds engage the rear edges of the hot plates they will be folded across the other end folds and will be sealed by the heat from the hot plates. After the articles have been wrapped in the manner described they are fed along a supporting shelf or table 181 until they are disposed 55 above a delivery conveyor 182 by which they are discharged from the machine.

Operation

60 The operation of the machine may be summarized as follows: The boxes are fed into the machine in any suitable manner, as by a conveyor 20, and are discharged on the shelf or support 21. The strip of wrapping material is fed by the feed 65 rolls A and is severed by the knife 52 and is thereafter fed over the opening 26 in the support 27 by the feed rolls C. Thereupon the plunger 25 feeds the foremost box upwardly through the opening 26 and the wrapper which is disposed in the upward path of movement of the box is also fed upwardly to the position shown in Fig. 6. The plate 81 is then moved forwardly and folds the depending end 80 against the bottom of the 70 box and the box and wrapper are then fed by the 75

pusher plate 105, the end 80A being folded across the folded end 80 at the bottom of the box.

When the box and wrapper have been fed from the position X to the position Y in Fig. 6 the lower tuckers 121 are moved upwardly from the position shown in Fig. 7 to the position shown in Fig. 5, thus tucking the lower ends of the wrapper. The upper tuckers comprising the blades 140 and 141 then move downwardly to form the upper end tucks, these blades moving downwardly to such 10 an extent that they overlap the lower tucks.

After the tucks have been formed the shafts 144 and 145 are rotated causing the spindles 160 and 161 to fold the end folds at the rear face of the box forwardly across the end of the box and 15 across the tucks. The movement of the spindles 160 and 161 is limited by the guide strips 167, 167. The spindles are, however, held against the guide strips by the springs 166. After the spindles 160 and 161 have folded the ends of the wrapper as 20 described the wrapped article is again fed forwardly by the pusher plate action on the articles behind the article disposed in the position Y and the remaining end folds are folded across the 25 ends of the articles by the engagement of these folds with the edge of the hot plates 180, 180.

Although one specific embodiment of the invention has been particularly shown and described it will be understood that the invention is capable of modification and that changes in the 30 construction and in the arrangement of the various cooperating parts may be made without departing from the spirit or scope of the invention, as expressed in the following claims.

What I claim is:

1. In a wrapping machine, means for feeding an article and wrapper, means for folding and securing the wrapper around the article, means movable into and out of engagement with the lower ends of the wrapper for tucking the lower 40 ends of the wrapper against the ends of the article, means for operating said tucking means, subsequently acting means for tucking the upper ends of the wrapper against the ends of the article, and means for actuating said last named 45 means and moving said upper tucking means over the lower tucked ends after the withdrawal of the first named tucking means.

2. In a wrapping machine, means for feeding an article and wrapper, means for folding and 50 securing the wrapper around the article, means for tucking the lower ends of the wrapper against the ends of the article, subsequently acting means for tucking the upper ends of the wrapper against the ends of the article, means for actuating said 55 last named means and moving said upper tucking means over the lower tucked ends after the withdrawal of the first named tucking means, and means for making end folds of the wrapper across the ends of the article and over the tucked ends. 60

3. In a wrapping machine, means for feeding an article and wrapper, means for folding and securing the wrapper around the article, means movable into and out of engagement with the lower ends of the wrapper for tucking the lower 65 ends of the wrapper against the ends of the article, means for tucking the upper ends of the wrapper against the ends of the article, said last named means being movable over the lower tucked ends after the withdrawal of the first named 70 tucking means, and resiliently pressed means for making end folds of the wrapper across the ends of the article and over the tucked ends.

4. In a wrapping machine, means for feeding an article and wrapper, means for folding and 75

securing the wrapper around the article, means movable into and out of engagement with the lower ends of the wrapper for tucking the lower ends of the wrapper against the ends of the article, means for tucking the upper ends of the wrapper against the ends of the article, said last named means being movable over the lower tucked ends after the withdrawal of the first named tucking means, and resiliently pressed, 10 positively operated means for making end folds of the wrapper across the ends of the article and over the tucked ends.

5. In a wrapping machine, means for feeding an article and wrapper, means for folding and 15 securing the wrapper around the article, a member having tucking means for tucking the ends of the wrapper against the ends of the article, means for reciprocating said member and moving said tucking means along the ends of the article and wrapper to form the end tucks, means carried by said member for folding the ends of the wrapper across the tucked ends and article ends, and means for oscillating said member and moving said tucking means out of operative position 20 and said folding means across the ends of the article and wrapper to form the end folds.

6. In a wrapping machine, means for feeding an article and wrapper, means for folding and securing the wrapper around the article, members 30 having tucking means for tucking the ends of the wrapper against the upper ends of the article, means for tucking the other ends of the wrapper against the lower ends of the article, and means carried by said members for folding the ends of the wrapper across the tucked ends and article ends, said folding means being movable about axes parallel to the direction of movement of the tucking means.

7. In a wrapping machine, means for feeding 40 an article and wrapper, means for folding and securing the wrapper around the article, members having tucking means for tucking the ends of the wrapper against the upper ends of the article, means for moving said tucking means 45 along the ends of the article and wrapper to form the end tucks, means for tucking the other ends of the wrapper against the lower ends of the article, and means carried by said members for folding the ends of the wrapper across the tucked ends and article ends, said folding means being

movable about axes parallel to the direction of movement of the tucking means.

8. In a wrapping machine, means for feeding an article and wrapper, means for folding and securing the wrapper around the article, members having tucking means for tucking the ends of the wrapper against the upper ends of the article, means for moving said tucking means along the ends of the article and wrapper to form the end tucks, means for tucking the other ends of the wrapper against the lower ends of the article, means carried by said members for folding the ends of the wrapper across the tucked ends and article ends, and means for moving said folding means across the ends of the article and wrapper about axes parallel to the direction of movement of the tucking means to form the end folds.

9. In a wrapping machine, means for feeding an article and wrapper, means for folding and securing the wrapper around the article, members 20 having tucking means for tucking the ends of the wrapper against the upper ends of the article, means for reciprocating said member and moving said tucking means along the ends of the article and wrapper to form the end tucks, means for tucking the other ends of the wrapper against the lower ends of the article, means carried by said members for folding the ends of the wrapper across the tucked ends and article ends, and means for oscillating said members and moving 30 said folding means across the ends of the article and wrapper about axes parallel to the direction of movement of the tucking means to form the end folds.

10. In a wrapping machine, means for feeding 35 an article and wrapper, means for folding and securing the wrapper around the article, members having tucking means for tucking the ends of the wrapper against the upper ends of the article, means for moving said tucking means 40 along the ends of the article and wrapper to form the end tucks, means for tucking the other ends of the wrapper against the lower ends of the article, means carried by said members and movable relative thereto for folding the ends of the wrapper across the tucked ends and article ends, and means for moving said folding means across the ends of the article and wrapper about axes 45 parallel to the direction of movement of the tucking means to form the end folds.

JOHN VAN BUREN.
